(57) **CLAIM**

The ornamental design for a binocular grip, as shown and described.

DESCRIPTION

FIG. 1 is a top-front perspective view of a binocular grip showing my new design;

FIG. 2 is a bottom-front perspective view thereof;

FIG. 3 is a top-rear perspective view thereof;

FIG. 4 is a bottom-rear perspective view thereof;

FIG. 5 is a front elevational view thereof;

FIG. 6 is a rear elevational view thereof;

FIG. 7 is a left elevational view thereof;

FIG. 8 is a right elevational view thereof;

FIG. 9 is a top plan view thereof; and,

FIG. 10 is a bottom plan view thereof.

The broken lines immediately adjacent to the shaded area represent unclaimed boundaries of the design. The unshaded regions within or adjacent to the shaded area form no part of the claimed design. The remaining broken lines show unclaimed portions of the binocular grip that form no part of the claimed design.
